Mario Laguzzi, Long Island City, N.Y., assignor to Poirette Corsets, Inc., New York, N.Y.

Original design application Jan. 31, 1962, Ser. No.
68,582. Divided and this application July 11, 1962,
Ser. No. 70,878

Term of patent 14 years

(Cl. D20—2)

FIG. 1

FIG. 2 is a rear elevational view.

This application comprises a division of my copending application entitled Panty Girdle, Ser. No. D. 68,582, filed January 31, 1962.

I claim:

The ornamental design for a panty girdle, as shown and described.
